TENSION CONTROL DEVICE FOR A
WINDING APPARATUS

Henry E. Van Derhoef, Rochester, N. Y., assignor to Eastman Kodak Company, Rochester, N. Y., a corporation of New Jersey

Application November 19, 1937, Serial No. 175,492

11 Claims. (Cl. 242—75)

The present invention relates to a winding apparatus, and more particularly to an arrangement for controlling and varying the tension of a strip as it is being wound into a roll. While the present embodiment primarily relates to a mechanism for winding a strip of film base, it is apparent that such a mechanism is adapted to a wide variety of uses. The term "film" is, therefore, intended to be used in its generic sense to include all materials arranged in the form of a continuous web or strip.

One object of the invention is the provision of a mechanism for automatically controlling the tension of a film strip as it is being wound into a roll.

Another object of the invention is the provision of an arrangement whereby this tension may be gradually and uniformly varied as the roll increases in size, thus assuring a tightly wound roll.

A further object of the invention is the provision in a tension device, of an arrangement whereby the rate of change of tension may be readily and easily varied.

A still further object of the invention is the provision in a tensioning device of the class described, of an arrangement for automatically compensating for any slight momentary variation in the tension of the strip.

Still another object of the invention is the provision of a tension control device which may be readily applied to existing machines.

A still further object of the invention is the provision of such a tensioning device which is positive in its action, adjustable, simple in construction, relatively inexpensive to manufacture, and highly effective in use.

Another object of the invention is the provision of a tension control device which may be adjusted to automatically maintain a uniform tension on the film strip as the latter is being wound into a roll.

Yet another object of the invention is the provision of a mechanism for gradually increasing the torque applied to the take-up roll in proportion to the lineal speed of the film strip through the machine.

To these and other ends, the invention resides in certain improvements and combinations of parts, all as will be hereinafter more fully described, the novel features being pointed out in the claims at the end of the specification.

In the drawings:

Fig. 1 is a side elevation view of a portion of a machine for forming and winding a film base or

support, with the side plate removed, showing the relation thereto of a tension device constructed in accordance with the present invention;

Fig. 2 is a diagrammatic view of a portion of the structure illustrated in Fig. 1, showing the arrangement for controlling the torque applied to the takeup roller shaft;

Fig. 3 is a plan view of a tension device constructed in accordance with the preferred embodiment of the invention, taken substantially on lines 3—3 of Fig. 1, showing the arrangement for operating the device;

Fig. 4 is a plan view of a portion of the apparatus illustrated in Fig. 3, but on a larger scale and with parts in section, showing the arrangement for adjusting the throw of the pawl by which the rate of change in tension of the film strip may be varied; and

Fig. 5 is a vertical sectional view taken substantially on the lines 5—5 of Fig. 3, showing the arrangement of the mechanism for controlling the tension of the film strip as it is being wound onto the takeup roll;

Fig. 6 is a horizontal sectional view through the friction clutch members, and taken substantially on the line 6—6 of Fig. 2, showing the arrangement of the clutch parts.

Similar reference numerals throughout the various views indicate the same parts.

In the manufacture of photographic film, a suitable "dope" is applied to a coating wheel; and, when sufficient solvents have been removed, the dope is stripped off the wheel in the form of a continuous web or strip. This strip is then wound over suitable rollers in the drying or curing section of the machine to remove the remaining solvents. The cured strip is then wound onto a takeup roll, and forms what is known to the art as "film base" or support." During the passage of the strip through the machine, the marginal edges of the strip are slit off so that only the intermediate portion of the strip is wound into the roll on the takeup roller. The film base or support is then coated with the proper emulsion to form the desired type of photographic film.

Various methods of winding the film support have been used, and these methods have not been found exactly satisfactory. In one method, the first 200 or 300 feet of support were wound on the core at a rather high tension, the tension being eased off as the size of the roll increased, thus before the roll is completed several different tensions were used. In another method, the tension is adjusted at the start of the winding operation, and this tension is maintained throughout

the entire winding of the roll. The first method provides a roll which is in better shape, as a whole, when completed, although there is a difference in tension which, if not carefully changed, 5 may allow a slippage of the support on itself when being coated with emulsion, causing folds to occur at the points where the change in tension was first made. Again, there is considerable variation in the appearance of the support at 10 different points where the tension has been changed. In addition, there is a possibility that the operator may neglect to make the necessary changes in tension at the proper time, so that the desired results will not be secured. In the 15 second method, on the other hand, there is not enough initial tension to form a good base on which to build the roll, so that the end of the roll is likely to be too slack due to the fact that the tension is not changed while the roll is being 20 built up.

In order to overcome these difficulties, the present invention provides a mechanism whereby the tension will be automatically and positively controlled from start to finish of the winding 25 operation. The tension of the strip is preferably held substantially constant and uniform as the roll of film base is wound up, thus insuring a tightly wound roll which may be more readily and satisfactorily coated with the proper photographic emulsion. The tension of the strip is maintained by means of a spring actuated roller positioned in a loop of the film base being wound on the take-up roller. In winding certain strip materials, however, it may be desirable or 30 advantageous to gradually decrease or increase the strip tension as the material is wound up. The mechanism of the present invention may be easily, quickly, and effectively adjusted to provide for such varying tension, as will be later more 35 fully described.

Fig. 1 shows a portion of a machine for making film base or support in the form of a continuous web or strip. The cured strip F is led between a pair of slitting rollers 11 which slit or trim off 45 the marginal edges of the film strip. This trimmed support is then led, in a sinuous path, over a plurality of driven tension rolls 12 to the spaced idler rollers 13 and 14 between which a loop 15 of the strip is formed. A floating roller, 50 generally indicated by the numeral 16 and hereinafter more fully described, is arranged in the loop 15, and is horizontally movable to respond to momentary variation in the tension of the strip. The strip passes from the lower idler roller 55 14 to a takeup roller 17 mounted for rotation on the takeup shaft 18. It is the usual practice, to provide two takeup rollers 17 and 17' which are mounted on a frame, not shown, pivotally mounted about the axis of the gear 20 so that when 60 one roll 17 has been wound to the proper size, the strip may be cut and the full roll removed. The empty roll 17' is then swung into position to have a strip wound thereon.

The shaft 18 has mounted thereon a spur gear 65 21 which meshes with a spur gear 22 on the shaft 23. The latter also carries a variable-friction plate drive, generally indicated by the numeral 24, by which varying amounts of torque may be transmitted to the gear 22. This device comprises, in the present embodiment, a sleeve 19, 70 see Fig. 6, loosely mounted on the shaft 23 and carrying a gear 20 which is suitably connected to the driving means for the apparatus. By means of this arrangement, the sleeve 19 is continuously 75 and positively driven at a uniform speed. The

gear 22 is loosely mounted on the sleeve 19 and is positioned between an annular disk or portion 19a formed integral with the sleeve and a friction plate portion 19b splined on the sleeve. The portions 19a and 19b are provided with suitable facing material 19c which frictionally engages the opposite sides of the gear 22 to operatively connect the latter to the sleeve 19. The gear 22, in turn, drives the gear 21 to rotate the roller 17, the gear 21 being preferably made relatively wide 10 so that the shaft 18 may be slid axially to disengage the roller 17, as is apparent from an inspection of Fig. 6.

It will be readily understood from Fig. 6 that the torque transmitted from the constantly driven sleeve 19 to the loosely mounted gear 22 is directly proportional to the axial pressure applied to the friction plate 19b. In other words, the greater the applied pressure the greater the torque transmitted, and vice versa. This variation in pressure is controlled, in the present embodiment, by means of a "Sylphon" diaphragm 25 mounted on the end of the shaft 23 and operatively connected to the friction plate 19b, as best shown in Fig. 6. This diaphragm is connected 25 by a liquid line 26 to a similar diaphragm 27 mounted on a support 28 concentric with the axis 29, as shown in Fig. 2. It will be apparent from this figure, that if an increased pressure is applied to the diaphragm 27, the liquid, such as oil, will 30 transmit this pressure to the diaphragm 25 and its connected friction plate 19b to increase the pressure of the latter on the gear 22 so as to 35 transmit more torque thereto, and hence to the windup shaft 18. Conversely, if the pressure is reduced in the diaphragm 27, the pressure of the plate 19b on the gear 22 will be correspondingly 40 reduced to cause a reduction of the torque furnished in the gear 22. The latter thus receives varying amounts of torque depending on the 45 pressure or force applied to the friction plate 19b. As the friction drive or clutch 24 is of standard construction and does not per se constitute a part of the present invention, a further discussion is not deemed necessary to a full understanding of the present invention.

The pressure on the diaphragm 27 may be varied by means of a bellcrank 30 which is pivoted at 31 on a member 32 carried by the oil housing 33 of the diaphragm 27. One arm 34 of the bellcrank 30 is arranged to engage the diaphragm 27 while the other arm 36 is pivoted at 37 to one end of a rod 38, the other end of which is pivoted at 39 to a lever 40 carried by a shaft 41 movably mounted on a bracket 42 carried by the machine frame, all of which is clearly illustrated in Figs. 1 and 2. It will be apparent from inspection of Fig. 1, that if the shaft 41 is rotated or moved in a counter-clockwise direction, the rod 38 will be drawn to the left to pivot the bellcrank and 50 to bring the arm 34 thereof into contact with the diaphragm 27, as shown in Fig. 2. Further rotation of the shaft 41 will cause the arm 34 to 55 exert a pressure on the diaphragm 27, which pressure will be transmitted to the diaphragm 25 to increase the torque transmitted by the friction drive member 24. Thus, the amount of 60 torque transmitted to the gear 21, connected to the takeup shaft 18, may be controlled by the 65 movement of the shaft 41.

However, in order to insure satisfactory operation, the torque delivered to and the speed of the sleeve 19 is always in excess of that necessary to wind the strip on the roller 17. The actual torque transmitted to the gear 22 on the other hand, is 70 75

proportional to the pressure applied to the "Sylphon" diaphragm 25 and the friction plate 19b, as pointed out above. Due to this fact, there is always a slight slippage between the gear 22 and its driving member, the portion 19a and the friction plate 19b.

It is apparent to those in the art, that as the takeup roll 17 increases in size, the amount of torque required to rotate the roll also increases.

- 10 As pointed out above, this increased torque for rotation of the takeup shaft may be secured by gradually turning the shaft 41 in a counter-clockwise direction. To this end, the present invention provides an arrangement whereby this 15 turning, or tendency to turn, of the shaft 41 progresses gradually and in proper timed relation to the winding of the strip on the takeup roller 17. In addition, the present invention further provides an adjustment by which the rate of 20 increase of torque to the takeup shaft may be varied relative to the lineal speed of the strip through the machine to suit the type, width, and the thickness of the strip being wound.

16 to the left, as viewed in Fig. 1, upon any momentary decrease of strip tension. This movement of the roller 16 serves to increase the torque applied to the shaft 18 to reestablish the film tension to its former value, as pointed out above. It is apparent, however, that as the roller 16 15 moves to the left, the lower end of the spring 47 moves upwardly to thus shorten the spring and to correspondingly decrease the tension thereof. However, in order to maintain a constant film tension, as in the present example, the 20 length of the spring 47 must be held uniform. To secure this result, the present invention provides means for automatically and intermittently

The winding of the film strip onto the takeup roller 17 also pulls or tensions the portion of the strip F between the tensioning rolls 12 and the roller 17. This strip tension multiplied by the radius of the film roll, the radius being the lever arm of the strip tensioning force, equals the torque applied to the takeup shaft 18. This relation may be expressed by an equation, such as $TR = P$, where T is the strip tension, R the roll radius and P the applied torque. It is apparent from this equation that if P (torque applied) is held constant and R (roll radius) is increased, that T (strip tension) must correspondingly decrease to maintain the equation.

Now, for the purpose of illustration, consider a small increment of time in which P remains constant. During this interval the roller 17 is constantly rotated to wind up additional film, thus slightly increasing the roll diameter, the result of which is to also decrease the film tension, as pointed out above. As the strip tension thus momentarily decreases, the loop 15 increases in length and the floating roller 16 moves to the left, as viewed in Fig. 1, by means to be presently described. The roller 16 is mounted on the free end of an arm 43 of the shape best shown in Fig. 1, the other end of which is secured to the shaft 41, so that as the roller is thus moved, shaft 41 is rotated in a counter-clockwise direction to automatically apply more torque to the shaft 18, as above described. Thus any tendency of the strip tension to decrease, automatically increases the torque applied to the roll 17. This increase in torque to the winding shaft 18 compensates for the increase in diameter of the strip on roller 17 and thus restores the film tension to its original value. In addition, each increment of increase in the size of the roll 17 causes further movement of the roller 16 to apply still more torque to the shaft 18 so that such applied torque increases in proportion to the lineal speed of the strip through the machine. However, since the strip F is being fed from the machine at a constant lineal speed, the angular velocity of the takeup roller 17 must gradually decrease to compensate for its increasing diameter as the successive layers of film are added, thus maintaining a constant lineal windup speed. As this angular speed decreases, the slippage between the gear 22 and its driving-members 19a and 19b correspondingly increases, the sleeve 19 being driven at a constant speed as mentioned above.

The roller 16 is preferably spring actuated. To this end, the shaft 41 has mounted thereon a radially extending arm 46, the free end of which is fastened to the lower end of a tension coil spring 47, the upper end of which is secured to a movable rod 48, the purpose of which connection will be later described. The spring 47 thus tends to rotate the shaft 41 in a counterclockwise direction, and will automatically move the roller 16 to the left, as viewed in Fig. 1, upon any momentary decrease of strip tension. This movement of the roller 16 serves to increase the torque applied to the shaft 18 to reestablish the film tension to its former value, as pointed out above. It is apparent, however, that as the roller 16 moves to the left, the lower end of the spring 47 moves upwardly to thus shorten the spring and to correspondingly decrease the tension thereof. However, in order to maintain a constant film tension, as in the present example, the length of the spring 47 must be held uniform. To secure this result, the present invention provides means for automatically and intermittently moving the upper end of the spring 47 to compensate for the upward movement of the lower end thereof resulting from a leftward movement of the roller 16. By means of this arrangement, spring 47 may be held unvarying in length to exert a constant pull on the roller 16 to maintain a uniform film tension. However, a variable strip tension may be secured if desired, as later described.

To secure such movement of spring 47, the upper end thereof is secured to a vertical movable rod or member 48, as shown in Fig. 1. The lower portion of the rod 48, as shown in Fig. 1, is slideable in a guide 49 formed in a supporting bracket 50 secured, in any suitable well-known manner, to or formed integral with the machine frame. A suitable scale 51 may be mounted on the guide 49 to indicate the position of the member 48, as shown in Fig. 1. The intermediate portion 52 of the rod 48 is reduced in diameter and threaded to engage a correspondingly threaded opening 53, Fig. 5, of a sleeve, generally indicated by the numeral 54, and to be presently more fully described. The upper portion 56 of the rod 48, however, extends upwardly through an enlarged opening 57 in the sleeve 54 and projects above the latter, as shown in Fig. 5, the purpose of which construction will be described in due course.

which construction will be described in due course. The sleeve 54 has a reduced lower end portion 59 which extends downward through and is journaled in an opening 60 formed in the bracket 50. The portion 59 terminates in a shoulder 61 which extends over and is supported on the top 62 of the bracket 50, as clearly illustrated in Fig. 5. It is thus apparent that if the sleeve 54 is rotated in the bracket 50 in a clockwise direction, as viewed in Fig. 3, the threaded rod 48 will be moved upwardly relative to the sleeve 54, the sleeve being stationary axially. This upward movement of the rod 48 will correspondingly move the upper end of the spring 47 to compensate for the upward movement of the lower end thereof caused by the leftward movement of the roller 16. Thus the length of the spring 47 is held constant as the roll 17 increases in size to maintain the film strip under uniform tension during the entire winding operation. The tension of the film strip is thus determined by the tension maintained in the spring 47. It is apparent, however, that if the upper end of the spring 47 were not moved, the spring would grad-

ually decrease in length and the strip tension would correspondingly decrease.

The sleeve 54 may be rotated by means of a ratchet 64 loosely mounted on the sleeve 54, and connected thereto through a friction member or disk 65 positioned between the ratchet 64 and a collar 66 formed on the sleeve, as shown in Fig. 5. The ratchet 64 is resiliently maintained in driving engagement with the friction member 65 by means of a coil spring 67 which is wrapped around the sleeve 54, and is constrained between a ring 68 engaging the ratchet 64, and an internally threaded annular member 69. The tension of spring 67 may be readily and easily varied or adjusted by moving the member 69 along a corresponding threaded portion 70 of the sleeve 54 as will be apparent from an inspection of Fig. 5.

The ratchet 64 is moved by means of a pawl 72 which is carried by a radially extending arm 73 formed on a sleeve 74 loosely mounted on and surrounding the sleeve 54. The sleeve 74 is held in position between the collar 66 and the top 62 of the bracket 50, and is supported by the latter as clearly shown in Fig. 5. Upon movement of the sleeve 74 in a clockwise direction, as viewed in Fig. 3, the detent 75 of the pawl 72 engages the peripheral teeth 76 of the ratchet 64 to rotate the latter and thus the sleeve 54. The detent 75 is held in engagement with the teeth 76 by means of a spring 77 one end of which is secured to a post 78 on the pawl 72 while the other end is anchored to a post 78 on the arm 73, as best shown in Fig. 5.

The sleeve 74 may be moved or rocked by means of a crank arm 80 one end of which is provided with a fork or bifurcated member 81 secured to a post 82 carried by an arm 83 projecting radially from the sleeve 74 diametrically opposite the arm 73, as shown in Figs. 3 and 5. The opposite end of the crank arm 80 is threaded into a block 84 loosely supported on a pin 85 eccentrically mounted, in a manner to be presently described, on the side of the sprocket 86. The latter is connected by means of a chain 87 to a sprocket 88 mounted on a shaft 89 which supports one of the slitting rollers 11. Power is applied to either of the rollers 11, and this power may be transmitted to the other slitting roller 11 through a pair of spur gears 90 carried on the shafts 89, as will be apparent from an inspection of Fig. 1. Thus, the friction drive 24 is operatively connected with and controlled in timed relation to the rotation of the slitting rollers 11, or in other words, in timed relation with the lineal movement of the strip through the machine. In addition, the actual torque transmitted by the friction drive 24 is determined by the position of the spring-actuated floating roller 16. Therefore, the torque transmitted by the friction drive 24 to the shaft 18 will gradually increase as the takeup roller 17 is wound up, and this torque increases in the proper timed relation to the movement of the strip through the machine.

Those familiar with the art will readily appreciate the fact that the rate of application of torque to the shaft 18 will necessarily vary with the kind of strip being formed, as well as the width and thickness of such a strip. To this end, the present invention also provides an arrangement by which this rate of change of torque may be readily and easily varied. This adjustment is secured, in the present embodiment, by providing a means for adjusting the position of the pin 85 radially on the sprocket 86 which comprises an eccentric for the crank arm 80.

As the pin 85 is moved radially on the sprocket 86 the eccentricity of the crank arm 80 will be varied to thus control the throw of the pawl 72 for each rotation of the sprocket 86. This change in the eccentricity of the crank arm 80 will thus move the member 48 at a greater rate relative to the lineal speed of the strip through the machine. Thus, the rate of change in torque to the friction drive 24 will be varied relative to the winding up of the strip on the roller 17. To secure this change of eccentricity of the crank arm 80, the pin 85 is secured to or formed integral with a nut 92 which is mounted for movement axially on the reduced threaded portion 93 of a manually adjusting member 94. It is apparent from an inspection of Fig. 4, that if member 94 is rotated, as will be apparent from an inspection of Fig. 5, the nut 92 will move axially along the threaded portion 93 to thus move the pin 85 radially on the sprocket 86 to change the eccentricity of the crank arm 80. The member 94 may be manually rotated by means of a finger-piece 95 secured to or formed integral with one end of the member 94. The latter is journaled in a pair of spaced bearings 96 which are secured by screws 97 to upper and lower connecting members 98 and 99 respectively, the latter being fastened by screws 100 to the face of the sprocket 86, as clearly illustrated in Fig. 4. Thus, the eccentricity of the crank arm 80 may be readily and easily adjusted to vary the rate of change of the application of torque to the shaft 18 relative to the movement of the strip F through the machine. The member 94 is maintained against axial movement by means of a collar 101 and a shoulder 102, on the member 94, which engage the two spaced bearings 96. The collar 101 may be secured to the reduced end portion 103 of the member 94 by means of a pin 104, all as clearly shown in Fig. 4.

It is also apparent from the above description that to maintain a constant film tension, the spring 47 must be held constant in length to provide a uniform pull on the roller 16. To secure this result, the eccentricity of the rod 80 is adjusted so that the rod 48 will move the upper end of the spring 47 equally with the movement of the lower end thereof. However, such eccentricity may be adjusted so that the upper end of the spring 47 moves in smaller increments than the lower end so that the spring will gradually shorten. Such shortening of the spring 47 gradually decreases the tension thereon to provide a gradually decreasing strip tension. Maximum decrease is secured when the pin 48 is adjusted in alignment with the axis of the sprocket 86, in which case no movement of the rod 80 takes place. On the other hand, the eccentricity of the rod 80 may be so adjusted that the upper end of the spring 47 moves a greater amount than the lower end to gradually stretch the spring and thus increase the tension thereof during the winding operation to secure a gradually increasing tension in the film strip as the latter is wound up on the roll 17.

When the roll 17 reaches the desired size, the strip F is cut, and the supporting frame, not shown, is rotated about the axis 20 to bring the empty roll 17' into position to receive the strip. In starting a new roll, the threaded member 48 must obviously be returned to its original position. To this end, the ratchet 64 is provided with a handle 106 by which the ratchet may be readily rotated in a counter-clockwise direction, as viewed in Fig. 3, to move the member 48 downwardly to its initial position or to the initial setting of the spring 47. To limit this downward

movement, the upper threaded end 107 of the member 48 is provided with an adjustable stop 108 which is adapted to engage the top 109 of the sleeve 54 when the member 48 reaches its initial position.

The operation of the above-described device may be briefly summarized as follows: The film strip, after being formed on the coating wheels, is threaded through the curing section of the machine to remove the remaining solvent therefrom. The cured strip is then led between the slitting rolls 11 to trim off both marginal edges of the film. The trimmed sheet or strip is then led over a plurality of tension rollers 12 between which a loop 15 is formed to engage the floating roller 16. The finally cured strip is then wound up on a take-up roll 17 which is mounted for rotation on a take-up shaft 18. The latter shaft is connected by gears 21 and 22 to a drive shaft 23 which carries a friction drive member or clutch 24 which is driven in any suitable and well-known manner from the machine driving means. The driving member for the clutch is controlled by a "Sylphon" diaphragm 25 which is connected by an oil line 26 to a similar diaphragm 27. The arrangement is such that any increase in the pressure on the diaphragm 27 will automatically increase the pressure on diaphragm 25, thereby increasing the torque applied to the winding shaft 18.

Now as the strip is gradually wound up on the roll 17, the latter correspondingly increases in diameter. For each slight increase in diameter there is a corresponding momentary decrease in the tension on the film strip. This decrease in tension allows the floating roller 16 to be moved to the left under the action of the tension spring 47. Such movement of the roller 16 serves to rotate the shaft 41 in a counter-clockwise direction, and, through the rod 38 and the bell crank arms 36 and 34, increases the pressure on the diaphragm 27. This increased pressure is transmitted to the diaphragm 25 with a corresponding increase in torque to the shaft 18 to return the film tension substantially to its normal value. Thus a constant film tension is preferably maintained throughout the entire winding operation irrespective of the size of the winding roll 17. In addition, the amount of torque applied to the winding shaft 18 is gradually increased as the roll 17 increases in size.

As the roller 16 is thus moved, the spring 47 tends to shorten. However, in order to maintain a constant film tension, the length and hence the tension of the spring 47 must be held uniform. Therefore, the rod 48 is progressively moved upwardly to compensate for the movement of the roller 16, so as to maintain the spring 47 at a constant length to insure a constant strip tension. The tension of the spring 47 thus controls the tension maintained on the film strip. In order, however, that such changes in the spring may be made in proportion to the length of the film being wound through the machine, the movement of the rod 48 is regulated by a rotary sleeve 54. Sleeve 54 is, in turn, rotated by a ratchet 64 and a pawl 72, the latter being operated by a crank 80 eccentrically mounted on the side of the sprocket 86.

By varying the eccentricity arm 80 on the sprocket 86, the rate of change of torque on the clutch 24 may be varied in relation to the lineal speed of the strip through the machine. This change of eccentricity may be secured by means of an adjustable member 94 on which the arm 80

is supported. The sprocket 86 is connected to and driven from one of the slitting rollers 11 by means of a chain 87. The eccentricity of the rod 80 may be adjusted to continually vary the length of the spring 47 and thus afford a varying tension on the film strip, as the latter is being wound up.

It is thus apparent that the present invention provides an arrangement to automatically maintain either a constant or a varying tension on the film strip as the latter is being wound into a roll. Furthermore, the torque applied to the take-up shaft is also automatically increased as the roll increases in size, this increase being in proportion to the lineal rate of speed of the strip through the machine. In addition, this rate of increase in torque may be readily, easily, and quickly varied with the type, thickness, and width of the strip being wound.

While one embodiment of the invention has been disclosed it is to be understood that the inventive idea may be carried out in a number of ways. This application is, therefore, not to be limited to the precise details described, but is intended to cover all variations and modifications thereof falling within the spirit of the invention or the scope of the appended claims.

I claim:

1. In a film winding apparatus, the combination with a core on which a film strip is arranged to be wound to form a roll, means for driving said core, variable means for connecting said core to said driving means, of a supporting roller positioned in a loop of said strip, a spring operatively connected to said roller and arranged to yieldably move the latter, means operated by movement of said roller for controlling said connecting means, and means operated by said driving means for adjusting said spring to control the tension of said strip as the latter is wound onto said core.

2. In a film winding apparatus, the combination with a core on which a film strip is arranged to be wound to form a roll, means for driving said core, variable means for connecting said core to said driving means, of means including a ratchet for continuously adjusting said connecting means to progressively vary the tension of said strip as it is wound onto said core, means including an adjustable member for operatively connecting said ratchet to said driving means so as to be operated thereby, said member being adjustable to control the rate of change of tension on said strip and means for manually adjusting said member to control the movement of said ratchet.

3. In a film winding apparatus, the combination with a core on which a film strip is arranged to be wound to form a roll, means for driving said core, variable means for connecting said core to said driving means, of means responsive to variations in the tension on said strip for adjusting said connecting means, a threaded member, a resilient connection between said threaded member and said adjusting means, means for operating said threaded member to continuously and automatically adjust the length of said resilient connection to regulate the tension on said strip as it is being wound onto said core, and means for controlling said operating means in response to the lineal movement of said strip through said apparatus.

4. In a film winding apparatus, the combination with a core on which a film strip is arranged to be wound to form a roll, means for driving

- 5 said core, variable means for connecting said core to said driving means, means for adjusting said connecting means, of a rotatable threaded member, a resilient connection between said threaded member and said adjusting means, means for operating said threaded member to move said resilient connection and said adjusting means to change the tension on said strip as it is being wound onto said core, a roller engaging said strip, means operatively connecting said roller to said threaded member so as to cooperate with the latter to move said adjusting means to change the tension of said strip as it is being wound onto said core, and manual control means for adjusting the rate of rotation of said threaded member.
- 10 5. In a film winding apparatus, the combination with a core on which a film strip is arranged to be wound to form a roll, means for driving said core, variable means for connecting said core to said driving means, means for adjusting said connecting means, of a threaded member, a resilient connection between said threaded member and said adjusting means, means including a pawl and ratchet for operating said threaded member to move said resilient connection and said adjusting means to change the tension on said strip as it is being wound onto said core, means for operatively connecting said pawl and ratchet to said driving means and an auxiliary floating roller controlled by said strip and operatively connected to said resilient connection and cooperating therewith to control said adjusting means.
- 15 35 6. In a film winding apparatus, the combination with a plurality of rollers for advancing said strip through said apparatus, a core on which said strip is wound to form a roll, means for driving said core, variable means for connecting said core to said driving means, of an internally threaded rotatable sleeve, a support for said sleeve, a member engaging said threaded sleeve and movable axially relative thereto, a spring connecting said member and said variable means, a ratchet operatively connected to said sleeve to rotate the latter to move said member axially thereof to tension said spring so as to adjust said variable means to change the tension of said strip, a pawl for moving said ratchet, an eccentric member, a crank connecting said eccentric to said pawl, manual means for adjusting said crank relative to said eccentric to vary the throw of said pawl, and means for operatively connecting said eccentric to one of said rollers so as to be driven thereby.
- 20 40 55 7. In a film winding apparatus, the combination with a plurality of rollers for advancing said strip through said apparatus, a core on which said strip is wound to form a roll, means for driving said core, variable means for connecting said core to said driving means, of an internally threaded rotatable sleeve, a support for said sleeve, a member engaging said threaded sleeve and movable axially relative thereto, a coil spring interposed between and connecting said member and said variable means, a ratchet, friction means for operatively connecting said ratchet to said sleeve whereby the latter will be rotated upon movement of said ratchet to adjust said variable means to change the tension of said strip, a pawl for operating said ratchet, a pivoted arm on which said pawl is mounted, a crank movably mounted on said eccentric and connecting the latter to said arm, means for

moving said crank relative to said eccentric to vary the eccentricity of said crank, means for operatively connecting said eccentric to one of said rollers so as to be driven thereby, and means controlled by said strip and operatively connected to said spring and cooperating therewith for adjusting said variable means. 5

8. In a film winding apparatus, the combination with a plurality of rollers for advancing said strip through said apparatus, a core on which said strip is wound to form a roll, means for driving said core, variable means for connecting said core to said driving means, of an internally threaded rotatable sleeve, a support for said sleeve, a member engaging said threaded sleeve and movable axially relative thereto, a coil spring interposed between and connecting said member and said variable means; a ratchet, friction means for operatively connecting said ratchet to said sleeve whereby the latter is rotated upon movement of said ratchet to adjust said variable means to change the tension of said strip, a pawl for operating said ratchet, a pivoted arm on which said pawl is mounted, an eccentric mounted on said support, a crank movably mounted on said eccentric and connecting the latter to said arm, means for moving said crank relative to said eccentric to vary the eccentricity of said crank, means for operatively connecting said eccentric to one of said rollers 30 so as to be driven thereby, a floating roller engaging said strip and movable thereby, and an arm operatively connecting said floating roller and said variable means for controlling the latter from said floating roller. 35

9. In a film winding apparatus, the combination with a core on which a film strip may be wound to form a roll, means for driving said core, of means responsive to tension variations in said strip for adjusting said driving means, a variable spring operatively connected to said adjusting means, and means operated by said driving means for adjusting said spring in proportion to the lineal speed of said strip through said apparatus to control the rate of change of tension 45 of said strip.

10. In a film winding apparatus, the combination with a core on which a film strip may be wound to form a roll, means for driving said core, of means responsive to tension variations in said strip for adjusting said driving means, a variable spring operatively connected to said adjusting means, means for regulating said spring to control the tension of said strip, and means for adjusting said last mentioned means to regulate the rate of change of the tension in said strip. 55

11. In a film winding apparatus, the combination with a core on which a film strip may be wound to form a roll, adjustable means for driving said core, of a floating roller arranged in a loop of said strip and movable in response to tension variations thereof to adjust said driving means to increase the torque transmitted to said core as said roll increases in size, an adjustable 65 tension spring operatively connected to said roller, the tension of said spring determining the tension maintained in said strip, and means operated by said driving means and controlled by the lineal speed of said strip through said apparatus to maintain said spring at a constant 70 length to afford a uniform strip tension during the entire winding operation.
